CRUTCH

Filed Oct. 9, 1945

UNITED STATES PATENT OFFICE

2,473,671

CRUTCH

William J. Yackley, Peoria, Ill.

Application October 9, 1945, Serial No. 621,199

7 Claims. (Cl. 135—49)

1

The present invention relates to crutches and is more particularly concerned with a device whereby two ordinary crutches may be joined at the top to facilitate use, in difficult positions, by one-arm persons or by persons having both arms.

One of the objects of the invention is to provide a device of the character mentioned which can be readily locked to free the arm of a person having only one arm and as readily unlocked when the crutch is grasped again.

Another object of the invention is to produce a duplex crutch of simpler and more compact construction than what is disclosed in prior devices.

With the foregoing and other objects and advantages in view, the invention consists of the novel construction and arrangement of parts hereinafter described and claimed.

In the accompanying drawings illustrating the invention,

Figure 1 is a front elevation of the device.

Figure 2 is a vertical longitudinal section midway the crutches.

Figure 3 is an enlarged detail of the upper inside of one of the crutches, partly broken away.

Figure 4 is a vertical transverse section on line 4—4 of Figure 3.

Figure 5 is a detail similar in general to Figure 3 but showing a modified form of locking device.

Figure 6 is a vertical section on line 6—6 of Figure 5.

Figure 7 is an horizontal section on line 7—7 of Figure 5.

Figure 8 is an horizontal section on line 8—8 of Figure 5.

Figure 9 is an enlarged detail of the upper inside of a crutch with another modification of the locking device.

Figure 10 is a vertical section on line 10—10 of Figure 9.

Like numerals in the description and drawings designate the same parts of construction.

The two crutches 1 and 2 may be of conventional type and this invention may be readily applied or it can be built in at the factory. A spacer bar 3, constructed of light steel tube, preferably airplane type, joins both crutches at the top in a horizontal line just below the arm-pit pads 4. Cross bar 3 is provided with short lateral branches or arms 5, on the ends of which are secured half-discs 6 inverted and notched as at 7. The half-discs are preferably thin plates of suitable material and pivotally secured, centrally, as at 8, to a plate 9 which is attached to the inner side of the arm-pit support, as at

2

10. Plate 9 is provided with a depending projection or lug 11 which is inclined forwardly to the front standard of the crutch and pivotally secured thereto is an horizontally disposed latch

12 having an upwardly projecting tongue 13 on the inner end adapted to normally engage notch 7 of the half-disc. About midway between the ends of the latch is the pivotal connection 14 with the lug 11.

10 At its outer end the latch 12 is pivotally attached to a vertically disposed latch-operating rod 16, the lower end of which is pivotally attached to a projecting lever 17. This lever is pivoted to the hand grasp 18 of the crutch, as at 19, and lies along side of same. Mounted thereon is a slidable band 20 which contains the lever also and serves as a keeper to hold the lever normally horizontal, thus raising the latch rod 16 and depressing tongue 13 of the latch. This

20 normal position releases the engagement thereof with notch 7 and leaves the crutch free to move as desired. A latch spring 21 attached to the side of the crutch and to the latch between the latch release rod 16 and pivot 14 serves to main-

25 tain the latter in locked position when lever 17 is freed from keeper 20 and moves downwardly. It will be obvious, from the foregoing, that both crutches may be locked at the same time, if desirable, or just one crutch may be locked, depending largely whether the person is without a right or left arm. The advantage of this device is that a one-arm person can lock the crutches when it is desirable to use his one arm freely, as in locking or unlocking a door or doing something else which requires him to take his hand off the crutch.

30 The arm supports are preferably provided with adjustable shoulder straps 22 attached to plates 23 which project inwardly a sufficient distance 40 to position the straps well on the shoulders.

The modified form of locking device, illustrated in Figure 5, is used in conjunction with spacer bar 3 and a half-disc. In this form of the invention, the half-disc 24 is pivotally attached 45 centrally, as at 25, to a plate 26 which is fastened to the arm support like plate 9 in the preferred form. Plate 26 is provided with a vertically depending lug 27 which has a vertical slot 28 on the vertical median line, through which projects

50 the laterally bent end 29 of a locking-rod 30. The end 29 normally rests in an arcuate slot 31, in half-disc 24, which is positioned concentrically. At the bottom of said slot is a notch 32 which rod-end 29 engages when the locking rod 30 55 is drawn downwardly by handle 33 on its lower

extremity. This rod passes through a slot in the hand-grasp 18 of the crutch and a superimposed slotted plate 34. The slot in plate 34 is engaged by a crook or bend 35 in rod 30 to hold the latter down when the end 29 is drawn down into engagement with notch 32 of half-disc 24, thus locking the crutch in vertical position. A coil spring 36 is mounted on the upper part of the locking rod 30, between lugs on the outer face of stationary plate 26, and serves to lift the end 29 out of notch 32 when the handle 33 is pushed up, as in Figure 5.

Another modification of the locking device is illustrated in Figure 9. The lateral arms 5 of spacer bar 3 are secured to discs 37, which, as in the preferred form, are pivotally attached to plates 41 secured on the arm-pit supports 4. Discs 37 are pivoted centrally on pivot pins as at 38, and are provided concentrically with a plurality of convex projections 39 which protrude on their outer faces and are adapted to engage with concave recesses 40, in the abutting plates 41. These recesses are arranged concentrically with the pivot pins 38 and register with projections 39. Coil springs 42 are mounted on pins 38 between the heads thereof and discs 37 with sufficient play to permit disc 37 to be partially rotated and its projections seated as desired, thus allowing the crutches to be locked and unlocked. The discs 31 in this form of the invention are turned by hand.

Having thus described my invention, what I claim as new and desire to secure by Letters Patent is:

1. In combination, a pair of crutches, each of said crutches having an arm-pit support, a hand grasp on each of said crutches, a spacer element extending between said crutches, a plate carried by each end of said spacer element, a plate provided with a notch on each of said arm-pit supports, the plates of said spacer element being pivotally secured to the plates respectively of said arm-pit supports, a pivoted latch on each of said crutches and adapted to engage with the notch of the plate of said arm-pit support complementary thereto, means on said hand grasps for operating said latches, and means for holding said latches in engagement until released by the means on said hand grasps.

2. The construction set forth in claim 1 wherein in said holding means comprises a movable keeper on said hand-grasps adapted to maintain said latches normally in open position.

3. In combination, a pair of crutches, each of said crutches having an arm-pit support, a spacer element adapted to suitably space said crutches apart at the arm-pit supports, a plate secured to each arm-pit support, a plate secured to each end of the spacer element and pivotally mounted on the complementary plate of said arm-pit support, an arcuate slot in each spacer element plate positioned concentrically about the pivot and provided with a median notch, a vertically slidable rod mounted on the rear face of each plate secured to the arm-pit supports and provided with

a lateral projection adapted to engage said arcuate slot, and means on the hand-grasps of the crutches for engaging and disengaging said projection and said median notch.

5. In combination, a pair of crutches, each of said crutches having an arm-pit support, a spacer element adapted to suitably space the crutches apart at the arm-pit supports, two sets of concentrically pivoted plates, one plate of each set secured to the respective arm-pit supports and the other one of each set of the respective ends of the spacer element, yieldable pivot pins joining the plates of the respective sets, and a plurality of concentrically disposed surface irregularities on the abutting faces of said plates adapted to be put in engagement with each other by turning the plates which are secured to the spacer element.

6. In combination, a pair of crutches, each of said crutches having an arm-pit support, a hand grasp on each of said crutches, a spacer bar extending between said crutches and having its ends thereof connected to said crutches contiguous to the arm-pit supports of the latter, a locking device in association with each of said arm-pit supports, and means on the hand grasps of the crutches for operating said locking devices.

7. In combination, a pair of crutches, each of said crutches having an arm-pit support, a hand grasp on each of said crutches, a spacer bar extending between said crutches and having its ends thereof connected to said crutches contiguous to the arm-pit supports of the latter, a plate provided with a notch on each of said arm-pit supports, a latch on each of said crutches and adapted to coact with the notch of the plate complementary thereto, and means on the hand grasps of the crutches for moving the latches into and out of engagement with the respective notches of said plates.

8. In combination, a pair of crutches, each of said crutches having an arm-pit support, a hand grasp on each of said crutches, a spacer bar extending between said crutches, a disc pivotally mounted on each of said arm-pit supports and fixedly secured to the adjacent end of said spacer bar, said disc being provided with an inter-engageable means, and a locking element operatively connected to each disc and movable into and out of engagement with said engageable means.

WILLIAM J. YACKLEY.
